UNITED STATES PATENT OFFICE.

JOHN F. STEWARD, OF CHICAGO, ILLINOIS.

HARVESTER-FRAME.

SPECIFICATION forming part of Letters Patent No. 396,245, dated January 15, 1889.

Application filed May 19, 1888. Serial No. 274,413. (No model.)

To all whom it may concern:

Be it known that I, JOHN F. STEWARD, a citizen of the United States, residing at Chicago, in the county of Cook and State of Illinois, have invented certain new and useful Improvements in Harvester-Frames, of which the following is a full, clear, and exact specification.

Figure 1 is a perspective view of the main portion of the frame having my improvement applied thereto. Fig. 2 is a top plan view of one of the quadrant-racks in which the axle is supported, showing the connection of the braces thereto.

15 In practice it is found that most harvesting-machines on which binders are mounted become twisted out of their original form in consequence of the weight of the frame and binder and the strains to which they are subjected. 20 Usually the divider end of the finger-bar becomes lower than its opposite end, and in some cases the rear platform-sill sags at its outer end.

25 My improvement consists in a peculiar arrangement of braces whereby the frame may be properly aligned or brought to the required form or thrown so far out of alignment in a direction the reverse of that to which it naturally sags that the sagging action will cause 30 it to assume the proper form.

I have shown my improvement applied to a frame which is in other respects of substantially the same character as those now in general use.

35 A represents the front sill of the wheel-frame, and B the front sill or finger-bar of the platform-frame secured thereto.

C is the rear sill of the wheel-frame, D a truss located at the grain side of the main-wheel space and connecting the front and rear sills, and D' a corresponding truss on the outer or stubble side of the main-wheel space. These trusses may be of wood, if desired; but I prefer to make them of angle-iron, and I have 45 thus shown them in the drawings of well-known form, each truss consisting of a straight bottom member and a top member which is bent upward at the middle.

50 E and E' represent two slotted segmental rack-plates bolted to the inner sides of the respective trusses and designed to receive and

guide the ends of the main axle and the pins thereon in the customary manner.

In their general construction and arrangement the foregoing parts are similar to those now in use.

In applying my improvement I provide, as shown in the drawings, four braces, a, b, c, and d, and apply them in the peculiar positions shown in the drawings. The brace a extends 60 from the upper end of the segment-rack E of the grain-side truss to the front sill, A, at a point some distance from the truss. The brace c extends in a similar manner from the upper end of the segment-rack to the rear 65 sill, C, at a point some distance grainward from the truss. These two braces, it will be observed, extend one forward and the other backward; but they both extend grainward and downward from the top of the segment-rack and truss. The brace b extends from the lower part of the segment-rack E upward and grainward to the front sill, while the brace d extends in a similar manner from the lower 70 end of the segment-rack grainward and upward to the rear sill, C. The braces are securely attached at their inner ends to the sills, preferably by vertical bolts e and f. I prefer to unite the braces a and b at their front ends and the braces c and d at their rear ends, as 75 shown; but this connection is not necessary, the only requirement being that they shall have rigid connection with the sills at or near the points indicated. As shown in the drawings, the braces are extended through holes in 80 the segment-rack E, which is provided with lateral ears or offsets to receive them, and each provided with two nuts, one on the inside and the other on the outside, as shown in Fig. 2, this arrangement permitting each brace to be 85 secured firmly in position but adjusted endwise, as may be demanded. The segment-rack serves in effect as an intermediate device for connecting the braces with the top and bottom of the segment-rack. Any other suitable 90 mode of connection may be adopted, provided the braces occupy the position indicated in relation to the truss and sills.

While I prefer to secure the braces by the nut, in order to admit of their independent 100 longitudinal adjustment, they may be riveted or otherwise secured rigidly in place, provided

the proper precautions are taken to secure the required adjustment of the parts when they are assembled.

5 The raising of the outer end of the finger-bar is effected by shortening the brace *a* and lengthening the brace *b*. The elevation of the grain end of the rear sill is effected by shortening the brace *c* and lengthening the brace *d*.

In setting up the machines I prefer to give 10 them such degree of twist that when they spring or sag in action they will assume the required form—that is to say, the form in which the frame is flat and the front and rear sills parallel.

15 I am aware that adjustable braces have been variously applied in connection with wheel-frames and elevator-frames of harvesters.

Having thus described my invention, what I claim is—

20 1. In a harvester-frame, the front and rear sills, *A C*, and the connecting-truss *D*, in combination with the four diagonal braces ex-

tended grainward from the truss and connecting the same at top and bottom with the sills.

2. In a harvester-frame, the truss and the 25 front sill, in combination with the front braces, *a b*, extending forward and grainward from the top and bottom of the truss to the sill.

3. In a harvester-frame, the truss and the 30 rear sill, *C*, secured thereto, in combination with the braces *c d*, extending rearward and grainward from the top and bottom of the truss to said sill.

4. In a harvester-frame, the front and rear 35 sills and the connecting-truss, in combination with the four diagonal braces extended grainward from the truss and connecting the same at the top and bottom with the respective sills and each adapted for independent longitudinal adjustment.

JOHN F. STEWARD.
